FLAT KNITTING MACHINE

Kurt P. Spindler, Reading, Pa., assignor to Karl Lieberknecht, Inc., Reading, Pa., a corporation of Pennsylvania

Application July 10, 1937, Serial No. 152,955

5 Claims. (Cl. 66—129)

The present invention relates to flat knitting machines and more particularly to carriers and stops therefor.

The usual selvage or end stops for controlling the traverse of the carriers in plain fabric knitting are automatically controlled by the well known spindle mechanism. For certain operations in the manufacture of full-fashioned hosiery it is necessary to provide carrier stops which are intermediate to the end stops, for the purpose of controlling the knitting of reenforcing yarns. The inner stops have usually been operated manually.

The principal object of the present invention is to provide a simple fully automatic construction for limiting and controlling the traverse of inner selvage and reenforcing yarn carriers. To this end the present invention comprises the machine hereinafter described and particularly defined in the claims.

In the accompanying drawings Fig. 1 is an elevation partly in section, of the present invention applied to a multiple carrier knitting machine; Fig. 2 is a sectional elevation showing a section on line 2—2 of Fig. 1; Fig. 3 is a plan view of the mechanism shown in Fig. 1; Fig. 4 is a sectional elevation of the stop pins and bracket therefor; and Figs. 5 to 8 inclusive are detail views illustrating the pattern mechanism.

The machine shown in Figs. 1 and 2 comprises nine carrier rods 11 to 19 mounted for reciprocation in a bracket 20. Each carrier rod is connected with a carrier tube designated generally at 22. Only the carrier rods 13, 15, 16, 17 and 18 are arranged to be stopped inside the edges of the fabric, the remainder being adapted for full traverse between end stops. The usual end stops for the several rods are not shown in the drawings.

The carrier rods 15 and 17, arranged to apply reinforcing yarn to the right-hand side of the fabric, are provided with inner stop lugs or abutments 24, and the rods 16 and 18 which are arranged to apply reenforcing yarn to the left-hand side of the fabric are provided with similar stop lugs as shown in Fig. 3. Each stop lug 24 comprises a screw 26 threaded into plate 28 attached to the corresponding carrier rod, the screw being maintained in adjusted position by a lock nut 30. The carrier rod 13 is arranged for inside stops at both ends of the traverse as in block toe reinforcement, and one of the stop lugs therefor, designated at 32, is similar to the stop lugs 24 for the other carrier rods, while a second stop lug

34 is also provided which is of different construction as will hereinafter be described.

Cooperating with the stop lugs for each of the five carrier rods is a series of automatically operated stop pins of which four, designated at 36, 38, 40 and 42, are arranged to coact respectively with the stop lugs 24 of the carrier rods 15, 16, 17 and 18, while the fifth stop pin 44 is of different construction for coaction with the stop lugs 32 and 34 of the rod 13.

All of the stop pins are mounted in a bracket 46 having an arm 48 suitably secured to the machine frame. The stop pin 38 which is of the same construction as the pins 36, 40 and 42 is shown in detail in Fig. 4 and comprises a plunger 15 movable in a cylindrical opening in the bracket 46 and formed at the bottom with flat sides 48 which cooperate with a square key 50 to prevent rotation of the pin. The pin is normally retained in its upper or inactive position as shown in Fig. 20 by a spring 52. The pin is provided with a head 54 and is adapted to be depressed into stop position by means of a lever 56 pivoted on a fixed shaft 58. Upon actuation of the lever 56 the pin is moved into the path of the stop lug on the corresponding carrier rod.

The special pin 44 which coacts with both inner selvage stop lugs for the carrier rod 13, is formed to permit initial traverse of the rod 13 to such position that the stop pin may assume a 30 position between the stop lugs 32 and 34 of the carrier rod. To this end the pin 44 is made hollow as shown in Fig. 4 to receive an internal plunger 59 having a head 60 bearing against a cap 62 threaded on the pin 44. An internal spring 64 bears between the collar 60 and a shoulder 66 formed internally of the pin 44. An external spring 68 similar to the springs 52 for the other stop pins surrounds the pin 44 and bears between the upper surface of the bracket and the under 40 surface of the cap 62. An actuating lever 70 similar to the lever 56 bears against a head on the top of the plunger 59. The internal spring 64 is stronger than the external spring 68 so that the stop pin may, under the influence of the 45 lever 70, be depressed into the position shown in Fig. 4. The stop lug 34 as shown in Fig. 4 is formed with an inclined surface 72. It will be seen that after the lever 70 is depressed, the bottom of the stop pin 44 will ride on the incline 72 50 of the stop lug on the first left-to-right traverse of the carrier rod 13. During such action, the internal spring 64 yields, thus permitting the pin 44 to rise (as indicated by the dot-and-dash lines in Fig. 4) while the plunger remains de- 55

pressed by the lever 78. Thereafter the pin 44 drops into the space between the stop lugs 32 and 34 to determine the short traverse of the carrier rod in accordance with the positions of the 5 stop lugs.

The levers 56 and 70 for the stop pins are automatically operated by cams indicated at 74. As shown in Fig. 3, two cam drums 76 and 78 are provided, the former having three grooves to 10 permit application of cam segments 80 and the latter having two grooves for the application of similar segments. Thus five cams are provided, one for each of the actuating levers. As shown in Fig. 1 each lever is provided with a projection 15 82, acting as a cam follower, whereby upon actuation thereof by the proper cam segment, the corresponding stop pin is depressed into operative position.

The cams 74 are mounted on a shaft 90, the 20 rotation of which is automatically controlled in any suitable manner, preferably from the pattern mechanism of the machine. The connections by which the pattern mechanism is effective to operate the shaft 90 are similar to those described in 25 the co-pending application of Lieberknecht, Ser. No. 141,005, filed May 6, 1937, but will be briefly described here. The pattern mechanism comprises a chain 92 having a series of buttons 94 which are arranged to engage intermittently with 30 a bell crank lever 96, the latter being connected by a rod 98 with a second bell crank lever 100. The lever 100 has a yielding connection 102 with a bell crank 104 adapted to be rotated clockwise when the bell crank 96 is actuated by a 35 button 94 on the pattern chain. Rotation of the bell crank 104 moves a rod 106 to the right. The rod carries a fork 108 engaging a collar 110 on a stud 112, the latter having a cam roll 114, adapted to be brought into the path of a cam 116 on the 40 main cam shaft 118 of the machine. The stud 112 is mounted at the end of the lever 120, pivoted on a bracket 122 and connected at the other end by a link 124 with a pawl 126 which is arranged to advance a ratchet 128 on the shaft 90. 45 Each actuation of the bell crank 96 by a button on the pattern chain therefore results through the connections above described in the advance of the ratchet 128 by one tooth. The cam segments 80 are suitably attached to the cam drums 50 at such points as to cause actuation of the levers 56 and 70 at the proper times when the inner selvage stops for the carrier rods are to be determined.

The operation of the stop pins will be readily 55 understood from the foregoing description. For the pins 36, 38, 40 and 42 the cams are operated at appropriate times to depress the stops pins during the first traverse of the respective carriers. These stops are the inner stops determining the selvage reenforcement of the fabric. It will be understood that each of the carriers 60 15, 16, 17 and 18 also acts against a suitable end stop which is not shown in the drawings. The carrier 13 which is for block toe reenforcement, operates between two internal limiting positions, and it is for this carrier that the special

pin 44 is provided. Prior to the initial traverses of the carrier, the pin is yieldingly depressed into the path of the inclined lifting surface 72. On the first traverse, the pin rides on the lifting surface and drops into space between the stop lugs as shown in Fig. 4. During block toe reenforcement, the stroke of the carrier is determined by the setting of the lugs 32 and 34. Upon completion of the block toe reenforcement, the lever 70 is raised through the automatic operation of the pattern control and the pin rises out of the path of the stop lugs.

Although one specific embodiment of the invention has been described, it will be understood that the invention is not limited to the particular arrangement shown and described, but may be modified except as limited by the appended claims.

Having thus described the invention, I claim:

1. In a flat knitting machine, a carrier rod, a stop pin, actuating means to move the pin into operative relation with the carrier rod, said means acting on the pin in advance of the time required for coaction thereof with the carrier rod, an abutment on the carrier rod, and means associated with the carrier rod for lifting the prematurely activated stop pin over the abutment.

2. In a flat knitting machine, a carrier rod having a stop lug, a stop pin movable toward and from the carrier rod, actuating means for yieldingly setting the stop pin in operative position with relation to the carrier rod, and means forming an inclined surface on the carrier rod to lift the pin over the lug on the first traverse of the carrier rod after setting of the pin.

3. In a flat knitting machine, a carrier rod, a movable stop, abutments on the carrier rod, actuating means to move the stop into operative position in advance of the time it is required, and means for relatively moving said stop and abutments whereby subsequent movement of the rod causes the stop to become effective to stop the traverse of the carrier in each direction.

4. In a flat knitting machine, a carrier rod, a stop pin, actuating means to move the pin into operative relation with the carrier rod, said means acting on the pin in advance of the time required for co-action thereof with the carrier rod, an abutment on the carrier rod, and means associated with the carrier rod for moving the prematurely activated stop pin to permit the abutment to pass into operating position.

5. In a flat knitting machine, a carrier rod having a stop lug, a stop pin movable toward and away from the carrier rod, actuating means for yieldingly setting the stop pin in operative position with relation to the carrier rod in advance of the time required for co-action thereof with the carrier rod, and means associated with the carrier rod including cam and follower surfaces formed on the pin and carrier rod operative to move the pin into operating position with relation to the stop lug on the first traverse of the carrier rod after setting of the pin.

KURT P. SPINDLER.
